UNITED STATES PATENT OFFICE.

WILLIAM SCHRAGE, OF SHEBOYGAN, WISCONSIN.

DESIGN FOR A BENT-WOOD CHAIR-SEAT.

SPECIFICATION forming part of Design No. 28,665, dated May 17, 1898.

Application filed April 15, 1898. Serial No. 677,747. Term of patent 14 years.

To all whom it may concern:

Be it known that I, WILLIAM SCHRAGE, a citizen of the United States, residing at Sheboygan, in the county of Sheboygan and State of Wisconsin, have invented and produced a new and original Design for Bent - Wood Chair-Seats; and I do hereby declare the following to be a full, clear, and exact description of the same, reference being had to the accompanying drawings, forming a part thereof.

In the accompanying drawings, Figure 1 is a longitudinal vertical section, Fig. 2 is a bottom plan view, and Fig. 3 is a perspective view, of a bent-wood seat embodying my new design.

The leading or material feature of my design for a bent-wooden chair-seat consists in the front portion of the seat, curved in the arc of a large circle and terminating in a semicylindrical front lower edge. Starting from the

rear of the seat its upper face is concaved to the points 1 1 near its forward end, whence it curves downwardly in the arc of a large circle to the points 2 2, and finally terminating in a semicylindrical front lower edge, as 25 shown at 3 3. The lower or side pieces of the seat start with a short upward curve in the arc of a small circle, as at 4 4, and with a second long curve in the same direction, the latter terminating in an upward curve at the 30 back of the chair-seat, as shown.

Having described my invention, what I claim as new, and desire to secure by Letters Patent, is—

The design for a bent-wood chair-seat, as 35 herein shown and described.

WILLIAM SCHRAGE.
